UNITED STATES PATENT OFFICE.

DAVID W. WALKER, OF CENTRALIA, MISSOURI.

RIDGE CUTTER.

Application filed November 5, 1927. Serial No. 231,284.

The present invention relates to a ridge cutter and has for its prime object to provide an exceedingly simple frame construction which may be coupled to a tractor for moving 5 along the ground a plurality of pairs of discs disposed at an angle for throwing the dirt outwardly.

Another important object of the invention resides in the provision of a frame structure 10 in a ridge cutter of this nature wherein the parts may be assembled in a strong and rigid manner to attain a high degree of efficiency.

With the above and numerous other objects in view as will appear as the description proceeds, the invention resides in certain novel features of construction, and in the combination and arrangement of parts as will be hereinafter more fully described and claimed.

In the drawings:

20 Figure 1 is a side elevation of a ridge cutter embodying the features of my invention, Figure 2 is a top plan view thereof, Figure 3 is a rear elevation thereof, Figure 4 is an enlarged detail vertical section through the adjustable mechanism for mounting the discs on the frame, and

25 Figure 5 is a detail section through the frame taken substantially on the line 5—5 of Figure 2.

30 Referring to the drawing in detail it will be seen that numerals 5 denote a plurality of discs arranged in pairs. Each pair of discs are rotatably mounted on the extremity of yoke 6 depending from a shank 7 rockably 35 mounted in a bearing block 8. This clamp block 8 is rockable on a pintle 9 formed by extensions from jaw sections 10 and 11 which are bolted together as at 12. A nut segment 14 extends rearwardly from the section 11. A

40 crank 15 extends from the upper end of the shank 7 and has a spring pressed catch 16 engageable with the notches of the segment 14. An arm 17 rises from the bearing block 8 and has a bolt 18 extended therefrom with a nut 19

45 thereon. The arm 18 has a lateral extension 20 through which the bolt 18 extends, this lateral extension being adapted for engagement with notches of a segment 21 rising from the section 10. The parts thus far described 50 are conventional in the cultivator art and have been illustrated merely to bring out clearly the utility and advantages of the frame structure about to be described.

55 Referring to the frame structure in detail it will be seen that numerals 25 denote a pair of frame bars the forward ends of which are

fixed together and from which the bars extend rearwardly and diverge from each other so that the rear ends terminate in spaced relation. Hooked bolts 26 are mounted in the 60 rear extremities of the bars 27 with the hook ends disposed downwardly and supporting a cross bar 27 of sufficient length to extend between and beyond the rear ends of the frame bars 25. Rods 28 and 29 are fixed to the forward portions of the bars 25 one on top of one bar 25 and the other under the other bar 25. These rods 28 converge from their rear ends forwardly so that their forward ends are disposed one above the other and are apertured as at 29, said apertures being in vertical registry to receive a pin 30 for engagement with the draw bar, clevis or like of a tractor. 65

70 A cross bar 31 is disposed across the intermediate portions of the frame bars 25 being bolted to the upper surfaces thereof as at 32. Connecting rods 33 are pivotally engaged as at 34 with extensions 35 on the lower jaw sections 11 and extend forwardly to rest on top of the cross bar 31 being clamped thereon by means of a clamp rod 36 which is bolted to the frame bar 25 as at 37. Thus the cultivating parts of conventional construction are securely and rigidly mounted on the frame structure. The frame structure is very simple and because of the arrangement of its parts with respect to one another is very strong and durable. Furthermore this frame structure affords a mount for the cultivating parts allowing exceedingly desirable ease of 85 assembly and disassembly.

80 It is thought that the construction, operation, utility and advantages of this invention will now be clearly understood by those skilled in this art without a more detailed description 95 thereof. The present embodiment of the invention has been disclosed in detail merely by way of example since in actual practice it attains the features of advantage enumerated as desirable in the statement of the invention and the above description. It will be apparent that changes in the details of construction, and in the combination and arrangement of parts may be resorted to without departing from the spirit or scope of the 100 invention as hereinafter claimed or sacrificing any of its advantages.

105 Having thus described my invention, what I claim as new is:

110 In a ridge cutter of the class described, a frame consisting of a pair of frame bars with their forward ends fixed together and diverg-

ing from each other rearwardly so that the rear ends are disposed in spaced relation, a cross bar under the rear ends extending therebeyond, means for mounting the cross bar under the rear ends, and a pair of rods fixed to the forward ends of the frame bars to extend forwardly thereof one being fixed to the

upper surface of one bar and the other to the under surface of the other bar, said rods converging forwardly to terminate one above 10 the other, the forward ends being apertured in alignment.

In testimony whereof I affix my signature.
DAVID W. WALKER.
